UNITED STATES PATENT OFFICE.

HARRY W. DICKERS, OF CHICAGO, ILLINOIS.

FOUNTAIN-PEN.

Specification of Letters Patent. Patented Oct. 19, 1920.

1,356,195.

Application filed March 13, 1919. Serial No. 282,273.

To all whom it may concern:

Be it known that I, HARRY W. DICKERS, a citizen of the United States, residing at Chicago, in the county of Cook and State 5 of Illinois, have invented certain new and useful Improvements in Fountain-Pens, of which the following is a specification.

The invention relates to improvements in fountain pens.

10 One of the objects of the invention is to provide a new and improved means for attaching a holding clip to the outer pen cap.

Another object is to provide a means, in association with the clip, for introduction 15 into the pen barrel for collapsing the ink sack in self filling pens.

Other, further and more specific objects 20 of my invention will become readily apparent to persons skilled in the art from a consideration of the specification when taken in conjunction with the drawings, wherein—

Figure 1 is an elevation of a self filling pen embodying my invention.

25 Fig. 2 is a longitudinal central section taken on line 2—2 of Fig. 1.

Fig. 3 is a transverse section taken on line 3—3 of Fig. 2.

Fig. 4 is a perspective view of the pin to 30 be attached to the clip and used for the purpose of collapsing the ink sack.

In all the views the same reference characters are employed to indicate similar parts.

5 is the ordinary barrel of fountain pen 35 provided with a pen point 6 at one of its ends and provided with screw threads 7 engaging threads 8 of the outer inclosing cap 9.

Self filling pens are provided with a collapsible ink sack 10, usually made of rubber, and overlying the sack, within the barrel 5, is a flexible return strip 11 so that when the strip is pressed inwardly, the sack is collapsed and the resiliency of the sack. 45 causes it to become again expanded, thereby drawing ink into the sack in the usual manner. An opening 12 is made through the wall of the barrel for insertion of means for depressing the spring clip 11 and 13 50 shows the means for connecting one end of the clip to the barrel.

Located in the outer cap 9 is an inner cap 14, usually employed for more completely sealing the pen when the parts 5 and 9 are 55 screwed together, at 7 and 8. The inner cap 14 is a usual part of a pen, and re-

mains permanently in the position shown in Fig. 2, when the pen parts are assembled in finished condition.

I use the inner cap 14 as a means for holding the clip 15 in place. The outer cap 9 is perforated, as at 16, for entrance of the shank 17 of the clip. One side of the wall of the inner cap 14 is cut away, as at 18, to permit the inclusion of the shank 17 between the inner and outer caps. The clip 15 is bent, as at 19, so that the main portion 20, thereof, will lie substantially parallel with the outside surface of the cap 9. The clamping tongue 20 of the clip, is 70 provided with downturned ears 21, between which is pivoted the pin 22. The elongated end of the pin is substantially round, so that it may be inserted in the perforation 12, of the pen barrel. A pivot pin 23 passes 75 through the downturned ears 21 and the thicker portion 24, of the pin, which is provided with flat sides 25 and 26. When the pin is in a horizontal position, as shown in Fig. 2, the spring 27 bears against the 80 flat side 26 and yieldingly holds the pin in the position shown. When it is in dotted line position, shown in Fig. 2, the spring 27 bears against the flat side 25 and yieldingly holds it in this position. When the 85 pin is in this position, and the cap is removed from the barrel of the pen, then the pin 22 may be inserted in the perforation 12 for the purpose of collapsing the ink sack 10. When the pin 22 is in horizontal 90 position it is out of the way, but is always ready and convenient for the purpose described.

A new clip can conveniently be placed in position by removing the inner cap 14 and 95 placing the shank 17 of the clip in the opening 16 and then replacing the inner cap.

While I have herein shown a single embodiment of my invention, for the purpose of clear disclosure, it is manifest that many 100 changes may be made in the general arrangement and configuration of the parts within the scope of the appended claims.

Having described my invention, what I 105 claim is:—

1. A fountain pen cap having a pocket clip secured thereto, and a pin pivoted to said clip and movable to two positions in one of which it may be inserted into an opening in the barrel of the pen to compress the ink 110 sack therein.

2. A pocket clip having a shank and a

clamping tongue with a slot intermediate said shank and tongue; a pin, pivoted in said slot, and a spring to yieldingly retain the pin in a position substantially parallel with the axis of the pen and substantially at right angles thereto.

3. A fountain pen cap having a pocket

clip secured thereto, and a pin pivoted to said clip and for insertion into the barrel of the pen to compress the ink sack therein. 10

In testimony whereof I hereunto subscribed my name.

HARRY W. DICKERS.
